UNITED STATES PATENT OFFICE.

ROBERT W. HAULBROOK, OF MAYSVILLE, GEORGIA.

ADJUSTABLE LINT AND BRUSH BOARD.

Application filed December 31, 1921. Serial No. 526,311.

To all whom it may concern:

Be it known that I, ROBERT W. HAULBROOK, a citizen of the United States, residing at Maysville, in the county of Banks and 5 State of Georgia, have invented a new and useful Adjustable Lint and Brush Board, of which the following is a specification.

This invention aims to provide a novel form of lint plate for a cotton gin, the plate 10 being so constructed that it will withstand wear, and will be effective for removing the cotton from the brush, and be capable of adjustment toward and away from the brush.

15 It is within the province of the disclosure to improve generally and to enhance the utility of devices of that type to which the invention appertains.

With the above and other objects in view, 20 which will appear as the description proceeds, the invention resides in the combination and arrangement of parts and in the details of construction hereinafter described and claimed, it being understood that, with- 25 in the scope of what is claimed, changes in the precise embodiment of the invention shown can be made without departing from the spirit of the invention.

In the accompanying drawings:—

30 Figure 1 shows in vertical section, a portion of a cotton gin equipped with a device constructed in accordance with the invention; Figure 2 is a section on the line 2—2 of Figure 1; Figure 3 is a section taken approximately on the line 3—3 of Figure 2; and Figure 4 is a perspective view showing the lint plate.

In the drawings there is shown the frame 1 of a cotton gin, gin saws 2 being journaled 40 in the frame 1, and a rotary brush 3 being journaled in the frame, the lint flue appearing at 4—all as usual. The top member of the flue 4 is denoted by the numeral 5 and always carries a device of some sort, for removing the lint from the brush 3. This device, generally, is in the form of a fixed board, and is subject to several disadvantages. First, after the gin has been in use for a period of time, more or less extended, 45 it becomes necessary to set the brush 3 up toward the gin saws 2, and when the brush is set up toward the gin saws the brush is moved away from the top member 5 of the flue 4, and away from whatever instrumen-

tality is provided, on the top member 5, for 55 removing the lint from the brush 3.

Further, the lint removing means which is generally in the form of a board, becomes worn, and tends to cause the cotton to hang and choke up the lint flue 4.

In carrying out the invention, there is provided a lint plate 6, preferably made of metal, and including a body 7, there being a lip 8 projecting from the body, at an obtuse angle to the body, the lip carrying a flange 9 disposed approximately at right angles to the body 7, the lip and the flange defining an angle 10. Openings 11 are formed in the body 7 of the lint plate 6 and are adapted to register with elongated slots 12 in the top member 5 of the flue 4, the openings and the slots being adapted to receive clamping devices, such as bolts 14, whereby the lint plate may be held in position, as shown in Figure 1 of the drawings.

It will be obvious that the lint plate 6 can be adjusted toward and away from the brush 3, as occasion may demand. Further, the lint plate 6, being made of metal, will not become worn and hold the cotton, as is the case when an ordinary wood board is used. The specific shape of the lint plate, including, particularly, the lip 8 and the flange 9, makes the lint plate unusually efficient in detaching the cotton from the rotary brush 3.

What is claimed is:—

1. A cotton gin comprising a frame having a flue; a brush journaled on the frame and located adjacent to the flue; a lint plate, and means for securing the lint plate to the flue, the lint plate comprising a body having a downwardly inclined lip disposed at an obtuse angle to the body, the lip terminating in an upstanding flange disposed approximately at right angles to the body and extended circumferentially of the brush.

2. A cotton gin comprising a frame having a flue; a rotary brush journaled on the frame and disposed adjacent to the flue; a lint plate including a body having a downwardly inclined lip disposed at an angle to the body, the lip slanting into the flue and terminating in a flange extended circumferentially of the brush; and means for securing the plate to the flue for adjustment toward and away from the brush.

3. A cotton gin comprising a frame hav-

2

ing a flue, a brush journaled for rotation in the frame and located adjacent to the flue, and a lint plate secured to the flue for adjustment toward and away from the brush, the lint plate terminating in an upstanding flange disposed between the upper portion of the flue and the brush.

In testimony that I claim the foregoing as my own, I have hereto affixed my signature in the presence of two witnesses.

ROBERT W. HAULBROOK.

Witnesses:

W. F. MILLER,
G. P. BOONE.
